B. LIPSHITZ.
COMBINATION BEDSTEAD AND WARDROBE.
APPLICATION FILED NOV. 26, 1919.

1,338,741.

Patented May 4, 1920.

UNITED STATES PATENT OFFICE.

BENJAMIN LIPSHITZ, OF BROOKLYN, NEW YORK.

COMBINATION BEDSTEAD AND WARDROBE.

1,338,741.

Specification of Letters Patent.

Patented May 4, 1920.

Application filed November 26, 1919. Serial No. 340,895.

To all whom it may concern:

Be it known that I, BENJAMIN LIPSHITZ, a citizen of Russia, residing at Brooklyn, Kings county, State of New York, have 5 invented certain new and useful Improvements in Combination Bedsteads and Wardrobes, of which the following is a full, clear, and exact description.

This invention relates to improvements 10 in combined wardrobes and bedsteads, one of the objects of my invention being to provide a bedstead arranged to carry drawers, under the springs thereof, and a wardrobe at one end thereof. By means of my im- 15 proved combination a great saving of room is accomplished, as drawers, for the retention of clothes or other articles that can be folded, and a wardrobe within which wearing apparel can be hung, will be incorpo- 20 rated in a bedstead. Hence, wherever there is room for a bed, retainers for wearing apparel, etc., will be included, and as virtually three pieces of bed-room furniture 25 will be arrayed in one, much floor space will be saved.

I will now proceed to describe my invention in detail, the novel features of which will be pointed out in the appended claim, reference being had to the drawing, 30 wherein:

Figure 1 is a side elevation of an embodiment of my invention;

Fig. 2 is an end view thereof looking from the right in Fig. 1;

Fig. 3 is a cross-sectional view, the section being taken on line 3-3 in Fig. 1;

Fig. 4 is a sectional plan view, the section being taken on line 4-4 in Fig. 1;

Fig. 5 is a sectional plan view, the section being taken on a line 5-5 in Fig. 1; and

Fig. 6 is a sectional view on line 6-6 in Fig. 5.

As herein arranged, my invention con- 45 sists of a head section A, and a foot section B connected by rails 7 to support a spring member C. The head section A in this instance consists of posts 8 which support an arcuate extension 9, said posts being 50 connected by a cross-bar 9^a. The provision of the arcuate extension leaves a space 10 which I partly fill by means of a member 11. The arcuate extension is provided to

enhance the appearance of the bed, at the same time to lengthen same. The spring 55 member C will rest upon the side-rails 7 and cross-bar 9^a (see Fig. 6), the filler 11 being flush with the top surface of the spring; hence, the mattress 12 can overlap the end of the spring and rest upon the filler 11. 60 By this means a bed can be lengthened using the standard spring, and a long mattress used, the filler preventing the mattress, at the end, from sagging into the space between the cross-bar 9^a and inner wall of 65 the extension.

The wardrobe member B consists of a wall member 13, curved side members or panels 14 and 15, a door 16, hinged at 17 (in this instance), to panel 15, and shelves 70 18. Hooks may also be provided, if desirable. The wall member 13 (in this instance) fills the space between the post-members 19. Under the side rails 7 and between the post-members 8 and 19, I place 75 20 and 21 suitably supported in order that they can be opened and closed. It will be apparent that I am able by means of my improved combination to incorporate the pieces of furniture 80 in one, that is to say a bed, a wardrobe and dresser, and also to produce an extra long bed using the standard springs, but a longer mattress. Although the bed will be longer than the ordinary bed, it will have the appearance of a bed of usual length. 85

Having described my invention, what I claim is:

A bedstead comprising post members, side rails connecting the post members, a 90 cross bar connecting two of the post members, an arcuate extension carried by the post members having the cross bar, and a filler located in the space between the cross bar and arcuate extension, the top of said 95 filler being located somewhat above the top surface of the side rails and cross bar so as to lie flush with the top of a bed spring, carried by the side rails and cross bar.

Signed at New York city, N. Y., this 24th 100 day of November, 1919.

BENJAMIN LIPSHITZ.
